REVERSING VALVE MECHANISM

Stewart R. Ross, Windsor, Ontario, Canada, assignor of one-fourth to Frank A. Best, Windsor, Ontario, Canada

Application November 29, 1946, Serial No. 712,768

7 Claims. (Cl. 121—150)

1

This invention relates to novel and improved reversing valve mechanism for converting rotary motion into reciprocating motion in machines which use a fluid medium for power transmission.

An object of the invention is to provide novel and improved mechanism whereby the above indicated end is accomplished automatically, in large part through mechanism operatively responsive to the pressure fluid itself.

A further object of the invention is to provide means of the nature indicated in the last preceding paragraph, and in which a reversing valve is automatically and intermittently actuated between two operating positions, through the medium of a relatively incompressible fluid intermittently acted upon and opposed by a relatively compressible fluid.

A further object of the invention is to provide, in a system comprising a reciprocating, double acting power piston and a reversing valve, novel and improved means effective upon the reversing valve and responsive alternately to rise of pressure in opposed ends of the power cylinder, for actuating the reversing valve so as to periodically reverse the operating pressure in the power cylinder.

A further object of the invention is to provide, in a double acting power cylinder and reversing valve combination, a liquid impelled by pressure from a pressure source, a power piston reciprocable in a cylinder, reversing valve means for directing said liquid alternately against opposed faces of said piston, and a pair of chambers, one respectively in communication with each opposed end of said power cylinder, and with either of the opposed faces of said reversing valve, whereby a rise in pressure in either said end of said power cylinder becomes effective upon its respective fluid chamber to compress the fluid in said chamber to a critical pressure value, at which point said reversing valve is caused to reverse, and the liquid pressure is transferred to the opposite end of said power cylinder.

A further object of the invention is to provide, in a system comprising a reciprocating, double acting power piston and a reversing valve, novel and improved means effective upon the reversing valve to prevent damage to the system when unexpected resistance is encountered in the power piston output.

A further object of the invention is to provide apparatus of the nature generally indicated in the last preceding paragraph, whereby the power piston is permitted to continue to function in re-

2

stricted amplitude of stroke, even when unexpected resistance is encountered.

A further object of the invention is to provide apparatus of the nature indicated in the last two preceding paragraphs, whereby the reversing valve operates to reverse the direction of travel of the power piston when unexpected resistance is encountered, even though the power piston has not completed a full power stroke.

10 A further object of the invention is to provide, in a system comprising a reciprocating, double acting power piston and reversing valve, novel and improved means effective upon the reversing valve and responsive alternately to rise of pressure in opposed ends of the power cylinder, for actuating the reversing valve so as to periodically reverse the operating pressure in the power cylinder, in combination with means for establishing the maximum pressure to which the first said means is responsive.

Other objects and advantages of my invention will be apparent from a study of the following specification, in conjunction with the accompanying drawing, in which:

25 Fig. 1 is a schematic view, mostly in section, showing in conventional fashion various elements embodying my invention;

Fig. 2 is a view similar to Fig. 1, but showing some of the moving parts in a different operating position;

30 Fig. 3 is a perspective view, somewhat enlarged, showing the reversing piston valve;

Fig. 4 is a sectional view taken on the line 4—4 of Fig. 3; and

35 Fig. 5 is a fragmentary sectional view, somewhat enlarged, showing more clearly a corresponding portion of Fig. 1.

While the inventive subject matter here involved is susceptible of application to a variety of adaptations, it is here described in connection with the operation of a reversing valve associated with a double acting hydraulic powered cylinder and piston unit.

Referring to the drawing, and particularly to Figs. 1 and 2 which are schematic in nature, there is shown a power cylinder 10 in which a piston 11 reciprocates so as to impart appropriate driving motion to a connecting rod 12. The system is of the double acting type wherein the pressure is applied alternately and automatically in chambers 13 and 14 respectively adjacent the opposed pressure heads 15 and 16 of the piston. Hydraulic pressure is admitted to chamber 13 through conduit 17 and to chamber 14 through conduit 18, both said conduits having individual communi-

cation with a valve cylinder 19 within which a reversing valve 20 is reciprocable. As will later be described in greater detail the hydraulic fluid is impelled by a pump 23, and is thereby advanced through conduit 24 to the reversing valve cylinder 19 whence it proceeds through a selected one of the two conduits 17 and 18 to the chambers 13 and 14 alternatively so as to produce reciprocation of the power piston and connecting rod. Conduit 25 provides an exhaust path from the reversing valve cylinder 19 to the liquid sump 26 whence the fluid may again enter the pump 23 through a pickup conduit 27. As will now be apparent the hydraulic system is a completely enclosed one.

The reversing valve 20 including the means for automatic energization and control thereof, will now be described, reference being occasionally had to Figs. 3 and 4. Valve 20 in the embodiment here disclosed is a cylindrical piston element having an accurate leak-proof sliding fit in the hollow interior of cylinder 19. In lateral extent the valve is somewhat shorter than its housing chamber so that a limited amount of end clearance is available at either or both ends of the cylinder, the extent of such clearance being of course variable, and continuously changeable by the reciprocation of the valve. For convenience in further reference the end chambers on the left and right in cylinder 19 are designated, respectively, by reference characters 30 and 31.

Valve 20 is provided with two distinct pairs of liquid flow passages, one such pair 32 and 33, consisting of helical grooves, each extending around a respective semi-cylindrical portion of the valve periphery. Passage 32, in the position shown in Fig. 2, connects conduit 17 with exhaust conduit 25, and passage 33 connects conduit 18 with conduit 24 from the pump 23. The other pair of passages 35 and 36, are drilled through the mid-portion of valve 20, and are so spaced that in the position shown in Fig. 1, they connect, respectively, conduit 17 with conduit 24 and conduit 18 with conduit 25. It will be apparent that when the valve is in the position shown in Fig. 1, pressure from the pump is being applied, in chamber 13, to the left face 15 of piston 11, chamber 14 being open to exhaust. In the position shown in Fig. 2, pressure is applied, in chamber 14, to the right face 16 of piston 11, while chamber 13 is open to exhaust. Accordingly reciprocation of valve 20 produces reciprocation of piston 11 and connecting rod 12.

The general features of a double acting piston, in combination with a reciprocating reversing valve, are known to the art. The present structure has been described in some detail to permit the novel aspects of the invention, now to be described, to be better understood. Such novel aspects reside mainly in the self-actuating means whereby reversal of valve 20 is automatically accomplished without mechanical linkage or similar devices. The motion of the reversing valve in the present invention is responsive to pressure conditions existing in the power cylinder chambers 13 and 14, in operative conjunction with a compressible fluid in respective chambers in communication therewith.

Temporary maintenance of the valve 20 in the position of Fig. 1 is assured by a spring biased detent plunger 38, the top of which rests in a depression 38a in the bottom of valve 20. When forcibly dislodged from this position the valve may be urged to the right until detent plunger 39 seats in a depression 39a in the position shown

in Fig. 2. To maintain proper orientation of the valve, so that the various passages will always move to registration with their respective communicating conduits, shallow grooves 39b extend longitudinally along the outer surface of the valve, adjacent to the detent seats 38a and 39a, the grooves affording tracks for the detent plungers during reversal of the piston valve. The detent structure at the right end of Fig. 1 is more clearly shown in the enlarged fragmentary view, Fig. 5.

Communicating with conduit 17, and with left end chamber 30 of the reversing valve cylinder 19 is an air bell 40. It is directly connected to cylinder 19 through pipes 41 and 41a and a pipe 42 provides a shunt passage between the air bell and conduit 17. A needle valve 43 provides means for controlling the passage of liquid through shunt passage 42.

A similar air bell 44 is connected in like manner through pipes 45 and 45a with chamber 31, and through a shunt passage 46 with conduit 18, this shunt passage being likewise under the control of a needle valve 47. In assembling the apparatus a substantial volume of air, or other compressible gaseous fluid, is trapped in the upper portion 48 of bell 40 and in portion 49 of bell 44.

An operational cycle of the device herein illustrated will now be described. Assume that the various moving parts occupy the position shown in Fig. 1. Chamber 13 is open to hydraulic pressure from pump 23 through conduit 24, valve passage 35, and conduit 17. Chamber 14 is open to exhaust through conduit 18, valve passage 36 and conduit 25. Upon starting of pump 23 the initiation of operation increases pressure in chamber 13, and piston 11 moves rod 12 to the right. At the same time pressure begins to build up in bell 40 through piping 41 and 42, thereby compressing the air in the top 48 of the bell. When piston 11 reaches the right end of its structure, the pressure in bell 40 builds up to such an extent as to become effective on valve 20 through the branch 41a of pipe 41. The pressure thus developed moves reversing valve 20 to the right, namely, to the position shown in Fig. 2. This applies pressure within chamber 14 through conduits 18 and 24 and valve passage 33. It likewise opens the chamber 13 and the air bell 40 to exhaust. The progress of successive cycles will be obvious from what has already been said.

An additional advantageous feature of the invention is that if piston rod 12, or any mechanism with which it is operatively associated, encounters any unusual opposition or obstruction, such as might ordinarily cause damage to some portion of such mechanism, and which stops the power piston in its travel at any position, pressure will build up in one or other of the air bells 40 or 44, so as to actuate valve 20 and reverse piston 11 and rod 12. The stroke of the rod will of course be shorter than usual, but the abnormal operation of the device will no doubt become apparent to an operator so that the obstruction may be removed or the mechanism stopped. In any event such operation is preferable to injury to the machine.

The rate of travel of the main power piston may be varied either by increasing the pump pressure, by increasing the size of the conduits feeding the power cylinder chambers, or by selectively varying the effective liquid carrying capacity of said conduits. The rate of reversal of the valve 20 may be varied by varying the needle valve setting, or the air chamber capacity of the bells. Differential effects may be obtained by

providing one bell with a greater air capacity than the other.

What I claim is:

1. A hydraulic motor including a cylinder having a power chamber, a power piston receptacle in said cylinder, a conduit adapted to admit a relatively non-compressible fluid to said power chamber for the movement of said power piston in one direction and alternately, to open said power chamber to exhaust, means for moving said power piston in the opposite direction while said power chamber is open to exhaust, an oppositely movable valve in communication with said conduit and adapted, upon opposite valve movement, to control alternate entry and discharge of said non-compressible fluid into and from said power chamber, a fluid chamber in communication with said power chamber, a relatively compressible fluid in said fluid chamber and adapted to oppose the entry thereinto of said non-compressible fluid, whereby the entry of said non-compressible fluid into said fluid chamber produces compression of the compressible fluid therein, said fluid chamber also being in direct communication with said valve, whereby compression of the compressible fluid in said fluid chamber beyond a predetermined degree produces movement of the valve in one direction, and means for producing movement of the valve in the opposite direction.

2. A hydraulic motor including a double acting cylinder having a power chamber at each end thereof, a power piston reciprocable in said cylinder intermediate said power chambers responsive to admission of relatively incompressible fluid alternately to said power chambers, a pair of conduits, one communicating respectively with each said power chamber, for transmitting said incompressible fluid alternately to said power chambers, a reversing valve cylinder including a double acting reversing piston reciprocable therein, reciprocation of said reversing piston admitting said incompressible fluid alternately to each said power chamber while opening said other power chamber to exhaust, a pair of bell chambers each containing a compressible fluid, communication means from each said bell chamber to a respective power chamber whereby said incompressible fluid in said power chamber is effective to compress said compressible fluid in said bell chamber, additional fluid pressure communication means from each said bell chamber to a respective end of said reversing valve cylinder whereby pressure built up in said bell chamber is effective against a respective end of said reversing piston, and whereby reversion of said reversing piston is effected when pressure in one said bell chamber exceeds a predetermined amount.

3. A hydraulic motor including a double acting cylinder having a power chamber at each end thereof, a power piston reciprocable in said cylinder intermediate said power chambers responsive to admission of relatively incompressible fluid alternately to said power chambers, a pair of conduits, one communicating respectively with each said power chamber, for transmitting said incompressible fluid alternately to said power chambers, a reversing valve cylinder including a double acting reversing piston reciprocable therein, reciprocation of said reversing piston admitting said incompressible fluid alternately to each said power chamber while opening said other power chamber to exhaust, a pair of bell chambers each containing a compressible fluid, com-

munication means from each said bell chamber to a respective power chamber whereby said incompressible fluid in said power chamber is effective to compress said compressible fluid in said bell chamber, additional fluid pressure communication means from each said bell chamber to a respective end of said reversing valve cylinder whereby pressure built up in said bell chamber is effective against a respective end of said reversing piston, and whereby reversion of said reversing piston is effected when pressure in one said bell chamber exceeds a predetermined amount, and restraining detent means in operative engagement with said reversing piston and effective to retain said reversing piston at one or other end of its stroke until pressure in a respective bell chamber exceeds said predetermined amount.

4. A hydraulic motor including a double acting cylinder having a power chamber at each end thereof, a power piston reciprocable in said cylinder intermediate said power chambers responsive to admission of relatively incompressible fluid alternately to said power chambers, a pair of conduits, one communicating respectively with each said power chamber, for transmitting said incompressible fluid alternately to said power chambers, a reversing valve cylinder including a double acting reversing piston reciprocable therein, reciprocation of said reversing piston admitting said incompressible fluid alternately to each said power chamber while opening said other power chamber to exhaust, a pair of bell chambers each containing a compressible fluid, communication means from each said bell chamber to a respective power chamber whereby said incompressible fluid in said power chamber is effective to compress said compressible fluid in said bell chamber, additional fluid pressure communication means from each said bell chamber to a respective end of said reversing valve cylinder whereby pressure built up in said bell chamber is effective against a respective end of said reversing piston, and whereby reversion of said reversing piston is effected when pressure in one said bell chamber exceeds a predetermined amount, and adjustable flow control means in said communication means between each said bell chamber and said power chamber for predetermined the rate of pressure increase in each said bell chamber.

5. A hydraulic motor including a double acting cylinder having a power chamber at each end thereof, a power piston reciprocable in said cylinder intermediate said power chambers and responsive to admission of relatively incompressible fluid alternately to said power chambers, a pair of conduits, one communicating respectively with each said power chamber for transmitting said incompressible fluid alternately to said power chambers, a reversing valve cylinder including a double acting reversing piston valve reciprocable therein, reciprocation of said piston valve admitting said incompressible fluid alternately to each said power chamber while opening the other to exhaust, a pair of bell chambers each containing a compressible fluid, a pair of fluid transmitting pipes, one opening to each said bell chamber, and each such pipe having a first branch opening to a respective conduit, and a second branch opening to a respective end of said reversing valve cylinder, whereby fluid pressure flow from a conduit to either said bell chamber through a first said branch is also effective, through said second branch, against a respective end of said pis-

ton valve, and whereby reversion of said piston valve is effected when pressure in a bell chamber exceeds a predetermined amount.

6. A hydraulic motor including a double acting cylinder having a power chamber at each end thereof, a power piston reciprocable in said cylinder intermediate said power chambers and responsive to admission of relatively incompressible fluid alternately to said power chambers, a pair of conduits, one communicating respectively with each said power chamber for transmitting said incompressible fluid alternately to said power chambers, a reversing valve cylinder including a double acting reversing piston valve reciprocable therein, reciprocation of said piston valve admitting said incompressible fluid alternately to each said power chamber while opening the other to exhaust, a pair of bell chambers, each containing a compressible fluid, a pair of fluid transmitting pipes, one opening to each said bell chamber and each such pipe having a first branch opening to a respective conduit, and a second branch opening to a respective end of said reversing valve cylinder, whereby fluid pressure flow from a conduit to either said bell chamber through a first said branch is also effective, through said second branch, against a respective end of said piston valve, and whereby reversion of said piston valve is effected when pressure in a bell chamber exceeds a predetermined amount, and adjustable flow control means in said first branch for controlling the rate of pressure rise in said bell chamber.

7. A hydraulic motor including a double acting cylinder having a power chamber at each end thereof, a power piston reciprocable in said cylinder intermediate said power chambers and responsive to admission of relatively incompressible fluid alternately to said power chambers, a pair of conduits, one communicating respectively

with each said power chamber for transmitting said incompressible fluid alternately to said power chambers, a reversing valve cylinder including a double acting reversing piston valve reciprocable therein, reciprocation of said piston valve admitting said incompressible fluid alternately to each said power chamber while opening the other to exhaust, a pair of bell chambers, each containing a compressible fluid, a pair of fluid transmitting pipes, one opening to each said bell chamber, and each such pipe having a first branch opening to a respective conduit, and a second branch opening to a respective end of said reversing valve cylinder, whereby fluid pressure flow from a conduit to either said bell chamber through a first said branch is also effective, through said second branch, against a respective end of said piston valve, and whereby reversion of said piston valve is effected when pressure in a bell chamber exceeds a predetermined amount, and restraining detent means in operative engagement with said piston valve and effective to retain said piston valve at one or other end of its stroke until pressure in an associated bell chamber exceeds a predetermined amount.
